UNITED STATES PATENT OFFICE.

LORENZO H. SPARKS, OF PITTSBURG, PENNSYLVANIA.

SASH-LOCK.

SPECIFICATION forming part of Letters Patent No. 659,457, dated October 9, 1900.

Application filed July 26, 1900. serial No 24,879. (No model.)

To all whom it may concern:

Be it known that I, LORENZO H. SPARKS, a citizen of the United States of America, residing at Pittsburg, in the county of Allegheny and State of Pennsylvania, have invented certain new and useful Improvements in Window-Sash Locks, of which the following is a specification, reference being had therein to the accompanying drawings.

10 This invention relates to certain new and useful improvements in sash-fasteners, and has for its object to construct a device which may be conveniently attached to a window-frame and operated so as to hold both the upper and lower sash at any desired point and lock the same in position.

Briefly described, the invention consists of a clamping-bar which is pivotally held on a plate attached to the inner face of the window-frame, said bar being pivotally connected near its upper end to a rod which extends outwardly through the frame at the front thereof and is provided with a right-hand thread to receive the thread formed on the operating-nut, the latter being provided with exterior threads and cut left hand or in opposition to the interior threads to operate in the threaded socket which is countersunk in the window-frame.

30 In describing the invention in detail reference is had to the accompanying drawings, forming a part of this specification, and wherein like numerals of reference indicate corresponding parts throughout the several views, in which—

Figure 1 is a front view of a portion of a window-frame and the sash, showing my improved device in position. Fig. 2 is a side view of the frame with the sash in section, 40 showing the holder in position. Fig. 3 is a horizontal sectional view taken on the line 3 3 of Fig. 2. Fig. 4 is a detail perspective view of the holder with the operating-nut removed. Fig. 5 is a side view of the operating-rod which is arranged in the window-frame.

45 Referring to the drawings by reference-numerals, 1 indicates the stile or side of the window-frame, 2 the lower sash, and 3 the upper sash, both being of the ordinary form of construction. Adjacent to the meeting rails of the sash I cut away a part of the weather-strip 4 of the frame, and in this cut-

away portion I place in the frame, preferably recessed therein, a plate 5, which has pivotally secured to its center a clamping-bar 6, 55 the ends 7 of which are turned outwardly at right angles to the bar and are adapted to have their inner faces engage with the sash-rails 2 3, the one end engaging with the lower sash and the other end with the upper sash. 60 Near the upper end of the clamping-bar 6 I pivotally attach thereto the inner end of the operating-rod 8, which is arranged within the recess 9 on the inner face of the frame and extends outwardly through the frame, 65 having its extending end provided with screw-threads 10. This screw-threaded end of the operating-rod 8 extends through the threaded socket 11, which is countersunk in the outer face of the frame and is adapted to receive the exteriorly-screw-threaded shaft 12 and the adjusting or operating nut 14, that is mounted upon the threaded end 10 of the operating-rod. The threads 10 of the operating-rod and the interior threads of the adjusting or operating nut are of right-hand 70 construction, while the threads of the socket 11 and the shaft 12 are of left-hand construction, or vice versa, so that when the adjusting-nut is loosened or tightened (according to the cut of the threads) the operating-rod 75 will be moved outwardly or forced inwardly, and the clamping-bar consequently engages with the sides of the sash or disengages therefrom. For instance, we will presume that 80 the threads of the shaft 12 and socket are of left-hand construction. Consequently the nut 14 is turned to the right, and the right-hand threads on the operating-rod will cause this rod to be brought outwardly. Upon turning the nut 14 in the opposite direction the operating-rod 8 will be forced inwardly, and the end 7 of the bar 6 will be removed from engagement with the sash-rail, and the outer face of this end will be forced into engagement with the walls of the groove in the frame or into engagement with the weather-strip of the frame, permitting the sash to be readily removed, if desired.

It will be noted that various changes may 100 be made in the details of construction without departing from the general spirit of my invention.

Having thus fully described my invention,

what I claim as new, and desire to secure by Letters Patent, is—

1. In a window lock, or holder, the combination with the frame, of an operating-rod arranged thereon and extending outwardly through the frame with its extending end threaded, a clamping-bar pivotally secured to the inner face of the frame with one end of said rod pivotally connected thereto, and an adjusting-nut mounted on the other end of the rod for actuating said clamping-bar to move the same into or out of engagement with the sash, substantially as described.
2. The combination with a window frame and sash, of a clamping-bar pivotally secured to the inner face of the frame and provided with angular ends, an operating-rod pivotally connected to said clamping-bar and extending outwardly through the frame, a threaded socket countersunk in the outer face of the

frame and through which said operating-rod extends, and a clamping-nut mounted on the rod and engaging said threaded socket, substantially as described.

3. A window lock and holder consisting of a clamping-bar which is pivotally secured to the inner face of the frame and is provided with angular ends, an operating-rod pivotally connected to said clamping-bar and extending through the window-frame, and means engaging said rod for actuating the clamping-bar to engage the angular ends of the latter with the sash, substantially as described.

In testimony whereof I affix my signature in the presence of two witnesses.

LORENZO H. SPARKS.
